UNITED STATES PATENT OFFICE.

GEORGE E. STILLMAN, OF PROVIDENCE, RHODE ISLAND.

FAUCET.

SPECIFICATION forming part of Letters Patent No. 767,849, dated August 16, 1904.

Application filed April 1, 1904. Serial No. 201,152. (No model.)

To all whom it may concern:

Be it known that I, GEORGE E. STILLMAN, a citizen of the United States, residing at the city of Providence, in the county of Providence and State of Rhode Island, have invented certain new and useful Improvements in Faucets, of which the following is a specification.

My invention relates to water-faucets adapted for set-bowls and sinks of that class of faucets having a push-plug to operate in opening the valve; and the object of my invention is to simplify the structure pertaining to the valve proper.

15 The invention consists in the combination and arrangement of parts, as hereinafter described, and specifically set forth in the claims.

In the accompanying drawings, Figure 1 represents a central sectional view of a faucet or basin-cock adapted for a set-bowl and illustrating the normal position of the parts embodying my improvements as when the supply is shut off. Fig. 2 is a partial sectional view of the faucet, showing the position the 25 operating parts assume as when the supply is in force. Fig. 3 is a sectional view taken on line X X of Fig. 2, showing the casing for the valve-operating parts. Fig. 4 is a view, partly in section and partly in elevation, of a 30 faucet or sink-cock having my improved valve structure applied therein.

Like letters of reference indicate like parts.

Referring to Fig. 1, A is the body or shell of the faucet, having a partition b, which divides the supply-chamber c of the faucet from its discharge-chamber d. The partition b is provided with a screw-threaded opening to receive the threaded end of a tubular casing B, and said casing is firmly secured in place 40 in the faucet and of a length to extend above the discharge-chamber therein. The lower end of the casing B is made solid, as at e, and which portion has at its upper face an integral annular flange f, which surrounds a vertical opening g, communicating with another opening, g', that enters the discharge-chamber d of the faucet-shell A. The casing B is further provided with two series of perforations h h, extending vertically throughout its 45 solid portion e, and each series of perfora-

tions is formed near to the opening g' thereof, as shown in Figs. 1, 2, and 3.

The upper end of the casing B has an interior screw-threaded portion to receive a screw-plug i, which has an enlarged annular flange 55 i' of a diameter equal to the exterior diameter of the casing B. A packing-ring j is interposed between the upper end of the casing B and flange of the plug i. The plug i is provided with a centrally-circular opening, one 60 part of which is formed conical, as at k, whose larger end extends from the bottom face of said plug and terminates near the middle portion therein with a straight concentric opening, as shown.

65 The conical part of the opening k of the plug i forms a seat for an auxiliary valve l, said valve having an enlarged central portion exposing a conical surface to contact with the seat k and a concentric circular stem of a 70 length to project from the top face of the said plug. The lower end of the conical portion of the valve l is reduced in diameter, so as to form a shoulder for the end of a coil push-spring m to bear against. Said spring m is 75 interposed between the auxiliary valve l and a piston or main valve o.

The main valve o is loosely mounted in the casing B and has a recess formed in its bottom face to receive a flexible disk p, which is secured in place by a screw r.

80 The faucet-shell A is screw-threaded at its upper portion to receive the threaded end of a tubular cap A', whose interior diameter is greater than that of the exterior diameter of 85 the casing B, so as to provide a clearance which forms a water-passage s. The cap A' is provided with a central vertical opening to receive the stem t of a knob t', which forms a push-plug to contact with the projecting end 90 of the auxiliary valve l. A packing-ring v is interposed between the cap A' and the faucet-shell A. Another packing-ring, v', is mounted on the top face of the cap A' and surrounds the stem t of the push-plug, said ring being 95 held in place by a gland-nut w, which is screw-threaded upon its interior surface to engage the threaded end of said cap.

When the faucet or basin-cock is closed, the parts which comprise the valve structure as- 100

sume the position shown in Fig. 1—that is to say, the water-pressure from the supply has passed through the perforations h h , thence between the peripheral surfaces of the main 5 valve o and casing B , thence into the chamber x , where the pressure is maintained until acted upon to discharge. The water-pressure being in the chamber x of the casing forces the main valve o and auxiliary valve l upon their respective seats and causes the supply to be shut off. 10 The vent or opening k in the plug i having a much smaller area than that of the area of the supply-chamber x easily permits of pressing down the push-plug t to force the auxiliary 15 valve l from its seat, and simultaneously with this movement the water-pressure from the inlet or supply c will release the main valve o from its seat to the position of parts shown in Fig. 2. The main flow of pressure thence 20 passes from the perforations h h , thence through the openings g and g' of the casing, and out through the discharge d in the arrow direction indicated in said figure. The clearance s is made between the casing B and the 25 cap A' of the faucet-shell for the purpose to allow the lesser pressure in the chamber x when the faucet is open to pass through the vent or opening k , thence into the chamber d' , and finally pass down through the said 30 clearance s into the discharge d . When the knob t' of the push-plug is released to close the faucet, the spring m immediately acts to carry the auxiliary valve l upon its seat, after which the pressure, being now confined within 35 the chamber x , causes the main valve o to bear upon its seat, and thus shut off the supply.

In Fig. 4 I show the casing which contains my valve structure as mounted in the partition of the body or shell of an ordinary sink-40 cock.

By my construction and arrangement of parts I form a valve structure for faucets that is simple, durable, and inexpensive to manufacture and at the same time a valve structure 45 having the advantage of taking the pressure from beneath the main valve to automatically close off the supply.

What I claim, and desire to secure by Letters Patent, is—

50 1. In a faucet, the combination, with the shell having a partition dividing the supply-chamber from the discharge-chamber therein, and a push-plug movable in the shell; of a valve structure, comprising a tubular casing 55 one end of which is made solid and provided with a series of perforations or ports extending longitudinally of the casing and also provided with an opening which forms an exhaust extending from the chamber of the casing and transversely through its solid end; a main valve loosely mounted in the chamber of said casing, and having a flexible disk secured thereto and arranged to close the exhaust therein; a screw-plug secured in the opposite end of said casing and provided with a

conical opening which forms a valve-seat; an auxiliary valve having a cone-shaped portion to rest on the seat of said plug and an integral stem projecting from the same; and a coil push-spring interposed between both said valves, 70 substantially as set forth.

2. In a faucet, the combination, with the shell having a partition dividing the supply-chamber from the discharge-chamber therein and a push-plug movable in the shell, a valve 75 structure, comprising a tubular casing having a solid end rigidly secured in the partition of the shell, said casing having its solid end provided with perforations extending from its chamber and entering the supply-chamber of the shell and also provided with an opening 80 extending from its chamber and entering the discharge-chamber of the shell; a piston-valve loosely mounted in said casing and having a flexible disk to close the opening in its solid end; a screw-plug secured in the opposite end of said casing and provided with a conical opening; an auxiliary valve mounted in the opening of said screw-plug and having an integral stem to contact with the push-plug; and a push-spring interposed between 85 said auxiliary valve and said piston-valve, substantially as set forth.

3. In a faucet, the combination, with the shell having a partition dividing the supply-chamber from its discharge-chamber and a push-plug movably mounted in the shell and entering its discharge-chamber; of a valve structure, comprising a tubular casing having a solid end arranged to rigidly secure in the 95 partition of the shell, said casing having its solid end provided with perforations extending from its chamber to the supply-chamber of the shell and also provided with an opening or exhaust extending from its chamber 100 and entering the discharge-chamber of the shell; a main valve loosely mounted in the chamber of said casing and having a flexible disk to close the exhaust-opening in the same; a screw-plug secured in the opposite end of 105 said casing and provided with a conical opening; an auxiliary valve mounted in the opening of said screw-plug and having a concentric integral stem to contact with the end of the push-plug; and a coil push-spring interposed between 110 said auxiliary valve and said main valve, substantially as set forth.

4. In a faucet, the combination, with the shell having a partition dividing the supply-chamber from the discharge-chamber therein, 115 said partition provided with a screw-threaded opening, and a push-plug movably mounted in the shell and entering its discharge-chamber; of a tubular casing having one end solid and provided with an exterior screw-threaded 120 surface to rigidly secure in the threaded opening of the partition, said casing extending in and having a lesser diameter than the interior 125 diameter of the discharge-chamber and provided in its solid end with a series of perfora- 130

tions constituting the sole inlet and also provided in its solid end with an opening forming the outlet extending from its chamber and communicating with the discharge-chamber; a main valve loosely mounted in said casing and having a flexible disk arranged to close off the supply; a screw-plug secured at the opposite end of said casing and provided with a conical vent forming a valve-seat; and
10 a spring-controlled cone-shaped valve mount-

ed in the seat of said screw-plug and arranged to contact with the end of the push-plug of the shell, substantially as set forth.

In testimony whereof I affix my signature in the presence of two witnesses.

GEORGE E. STILLMAN.
